CLAIM

The ornamental design for a package, as shown and described.

DESCRIPTION

FIG. 1 is a perspective view of a package showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of FIG. 1 shown in an alternate configuration;

FIG. 9 is a partial enlarged perspective view according to the broken rectangle in FIG. 1; and,

FIG. 10 is a partial enlarged perspective view according to the broken rectangle in FIG. 8.

The dashed lines shown represent unclaimed subject matter and form no part of the claimed design. The dash-dot-dot lines shown represent the partial enlarged views and form no part of the claimed design.

1 Claim, 8 Drawing Sheets
